UNITED STATES PATENT OFFICE.

CLARENCE E. N. LANCASTER, OF BOSTON, MASSACHUSETTS.

FILE FOR PROOF, COPY, &c.

SPECIFICATION forming part of Letters Patent No. 657,317, dated September 4, 1900.

Application filed December 26, 1899. Serial No. 741,498. (No model.)

To all whom it may concern:

Be it known that I, CLARENCE E. N. LANCASTER, a citizen of the United States, and a resident of Boston, county of Suffolk, and State of Massachusetts, have invented an Improvement in Files for Proofs, Copy, &c., of which the following description, in connection with the accompanying drawings, is a specification, like characters on the drawings representing like parts.

This invention has for its object the production of a strong, cheap, and efficient filing device for papers, particularly adapted for use in filing proof-sheets or copy in printing-offices and the like.

In accordance with my invention the filing device comprises an extended resilient holding-prong, a guard for the pointed end thereof, a brace, and an attaching portion, all formed of a single piece of stout wire bent into proper shape, one of its ends being screw-threaded to form a means of attachment for the device and the other end pointed and forming the prong.

Figure 1 is a perspective view of a filing device or copy-holder embodying one form of my invention, a piece of paper being shown on the prong. Fig. 2 is a side elevation thereof, showing the preferred mode of attachment, the support being shown in section; and Fig. 3 is a vertical transverse section of the device on the line $x-x$, Fig. 2, looking toward the left.

In carrying out my invention in the embodiment thereof herein shown I take a piece of stout strong wire a of proper length and bend it back upon itself at a' , the branches a and a^2 being then bent together in substantially a semicircle, as A, and from about the point 2 the branches diverge, the branch a^2 being carried back toward the screw-threaded extremity a^x of the branch a . I then bend the branch quite sharply toward the branch a , as at a^3 , carrying it over and around the latter to form an open loop a^4 , the free end of the loop extending substantially at right angles from the branch a to form a brace a^5 , the brace and arch A being at the same side of the straight branch a . The lower end of the brace a^5 is then bent to form a closed loop a^6 , the free end of the loop being turned around the brace at a^7 and extended substantially parallel to

the branch a to form a resilient holding-prong a^8 , the pointed extremity a^9 thereof being extended adjacent the bend a of the arch A, the bend forming a guard to protect the point of the prong.

The device is secured in place by screwing the threaded attaching portion a^x into the supporting object B, Fig. 2, until the loops a^4 a^6 rest against its face, and as the device is intended to be used with the prong a^8 in substantially-horizontal position below the guard the brace a^5 , with the loop a^6 , will operate to sustain the weight placed on the prong. At 65 the same time the weight is resisted by the stiffness of the branch a and the divergent branch a^2 , the looped inner end a^4 thereof bearing against the vertical face of the supporting object B. Thus one portion of the 70 device serves to support and strengthen another, and as the weight applied to the prong is below the attaching portion a^x there is no tendency of the device to turn about said portion a^x .

When a sheet is to be filed, it is bent and pushed onto the pointed end of the prong, as at M, Fig. 2, and passed along the prong until the head M' of the sheet is inside of the guard a' , (see Fig. 1,) the main body of the 80 sheet depending from the prong, so that it cannot be accidentally removed therefrom. When any particular sheet of a number on the prong is to be removed, a smart downward pull serves to tear it off without disturbing any of the other sheets, while access is readily had at any time to any sheet to examine its contents.

The device is particularly adapted for use in printing-offices where large quantities of 90 proof-sheets and "copy" are in constant use and which must be convenient of access for examination or removal, for the sheets can be quickly filed until needed.

The guard a' in connecting with the projecting arch A' protects the fingers and hands of the user from the sharp point of the prong.

Strength, durability, simplicity, and cheapness, combined with ease of manipulation, constitute the salient and important features 100 of my herein-described invention.

Having fully described my invention, what I claim, and desire to secure by Letters Patent, is—

1. A filing device made of a single piece of wire, bent upon itself and curved to form an arched guard, a straight prong having its outer end pointed and adjacent and protected by the guard, a supporting-brace connecting the inner end of the prong with the branch leading from the arched guard, and an attaching portion formed by the screw-threaded end of said branch extended beyond the brace. 5
2. A filing device made of a single piece of wire and comprising a resilient prong, a guard for the free, pointed outer end thereof, a brace at the opposite end of the prong, connected also with the guard, and an integral attaching portion screw-threaded and extended beyond the brace, the point of the prong and the screw-threaded attaching portion being formed by the two ends of the single piece of wire. 15
3. A filing device formed of a single piece of wire, the ends being substantially parallel and oppositely extended, one end being screw-threaded and the other end pointed to form a prong, the wire being bent at the inner end of the latter to form a brace, and looped around the threaded end portion, said end portion and the part of the wire leading from the loop being curved toward the point of the prong to form a guard for the point thereof. 25
4. A filing device formed of a single piece of wire and comprising a straight, resilient prong bent at its inner end to form a closed loop and an adjacent brace substantially at right angles to said prong, the free end of the brace being formed into an open loop and then extended forward toward the free end of the prong and bent upon itself thereat to form a guard, the wire from the guard being carried back through the open loop of the brace and threaded beyond the same, to form an attaching portion. 35
5. A filing device made of a single piece of wire one end comprising a resilient prong, a guard for the free, pointed outer end thereof, the other end of the wire extending from the guard oppositely to the prong and forming an integral attaching portion for the device, and a brace formed by the wire between the inner end of the prong and the guard, the brace engaging the attaching portion between its extremity and the guard. 45

In testimony whereof I have signed my name to this specification in the presence of two subscribing witnesses.

CLARENCE E. N. LANCASTER.
